CLAIM

The ornamental design for a video display module, as shown and described.

DESCRIPTION

FIG. 1 is a front elevational view of a video display module embodying my design;

FIG. 2 is a rear elevational view thereof;

FIG. 3 is a front and left side perspective view thereof; and,

FIG. 4 is a top plan view thereof.

The right side is a mirror image of the left side and the bottom is plane and unornamented.

FIG. 1

FIG. 2

FIG. 3

FIG. 4
